[57] CLAIM

The ornamental design for a connector housing for electrical wire, as shown and described.

DESCRIPTION

FIG. 1 is a top plan view of a connector housing for electrical wire, embodying our new design;

FIG. 2 is a front elevational view thereof;

FIG. 3 is a right side elevational view thereof the left side being a mirror image;

FIG. 4 is a cross sectional view thereof taken along the line 4—4 of FIG. 2;

FIG. 5 is a top, front, side perspective view thereof, the electrical wires and covers being shown in broken line for illustrative purposes only;

FIG. 6 is a bottom plan view thereof, and

FIG. 7 is a rear elevational view thereof.

FIG. 1

FIG. 2

FIG. 3

FIG. 4

FIG. 6

FIG. 7
